SELF-LABELING VISIBLY INDEXED JACKET
FILE

John T. Quigley, Los Angeles, Calif.

Application July 24, 1942, Serial No. 452,182

18 Claims. (Cl. 129—16)

This invention relates to a jacket file in which the visible indices are self-labeling.

Speaking more specifically the invention pertains to the provision of a file consisting of a multiple of separable jacket-holding means adapted to be removably assembled in containers in such a manner as to permit visible exposure of the entire group of indexed upper ends of the panels so assembled.

It is an object of this invention to improve upon means for indexing and filing documents or written or printed data by providing, in conjunction with a novel mounting means therefor, a combined record bearer and document container consisting of a jacket or casing quadrangular in cross section with open ends, there being space upon its outer surface for the reception of written lines and space within its interior for containing removable sheets and cards.

Another object of the invention is the provision for supporting the aforesaid jackets, a panel specially constructed with a view to supporting the jackets in an improved manner, said panel consisting of a base plate carrying longitudinally extending rods on which said jackets are slidably mounted in a detachable manner, the assembling of the labeled jackets upon said panel by means of said rods resulting in the alinement of the plane of the combined exterior label holding surfaces of the tops of said jackets within a plane adjacent to and parallel with the face of the supporting panel, thus bringing said index lines into a visible, readable position in relation to an observer of the face of the panel.

A further object of the invention is attained by combining the labeled jackets and the rods which support them in such a manner that the uppermost jacket of each panel, upon being moved upwardly to the limit of its travel, is automatically deflected upwardly and backwardly and then is stopped in a position wherein the plane of the exterior label-holding surface of said uppermost jacket is thereafter held at a right angle to the plane of the supporting panel and in a position wherein the index line of said jacket overlies the top end of the panel in a visible, readable, position.

Still another object of the invention relates to providing in the walls of the individual data-containing jackets, windows through which are displayed colors, thereby affording an additional index as to the contents of the jackets.

In the accompanying drawing is shown a mounting means for the jackets which resembles in some respects the sheet mounting means shown

in my co-pending application Ser. No. 431,097, filed February 16, 1942, now Patent No. 2,324,537, dated July 20, 1943.

With the foregoing and other objects in view, the invention resides in the novel arrangement and combination of parts and in the details of construction hereinafter described and claimed, it being understood that changes in the precise embodiment of the invention herein disclosed may be made within the scope of that which is claimed without departing from the spirit of the invention.

Referring to the accompanying drawing, which illustrates what is at present deemed to be a preferred embodiment of the invention:

Fig. 1 is a perspective view of the self-labeling visibly indexed jacket file, a corner portion of some of the jackets and inserts being broken away in order to provide extra drawing space on the sheet.

Fig. 2 is a vertical section of the structure shown in Fig. 1, the plane of section being set on the line 2—2 of Fig. 1.

Fig. 3 is a fragmentary transverse section taken on line 3—3 of Fig. 1.

Fig. 4 is a transverse section taken on line 4—4 of Fig. 1.

Fig. 5 is a face view of the jacket per se in its extended position.

Fig. 6 is a transverse section similar to Fig. 3, illustrating a modified locking means when wider files are employed.

Referring in detail to the drawing, the supporting structure of the device includes an upstanding base or back panel 5, said panel performing the function of a slide, which is desirably made of cardboard and should be of a sufficiently stiff character to support in a dependable manner the parts mounted upon it. In the drawing said panel is shown as an elongated, rectangular sheet 5 having along each side edge a forwardly directed (as viewed in Fig. 1) integral flange 6 or 7.

In Figs. 1 and 2 there are shown supported upon said panel, by means of parallel, spaced apart, resilient wire runs 8 and 9, three groups or packs of data-containing jackets, namely, an upper pack 11, middle pack 12 and lower pack 13. To aid in keeping said wire runs in place holes 15 are made through the panel spaced considerably down from its top and said wire runs 8 and 9 are each provided with a short backwardly directed run 16 which passes through one of said holes opposite to it, these runs being united by means of a cross run 17 which forms the mid-

length portion of the wire considered as a whole.

At the lower end of the device each of said wire runs 8 and 9 has its extremity 21 directed upwardly back of the panel and then bent forwardly upon the adjacent part of the wire so as to grip the lower edge of the panel, the panel preferably being noted to receive the bent part of each of the runs 8 and 9. These runs may be made of narrow strips of suitable material other than metal, but wire is at present deemed preferable.

The aforesaid three packs 11, 12 and 13 are made up of individual jackets 25 of bendable yet sufficiently stiff sheet material to hold its shape when subjected to but slight stress, each jacket assuming a shape quadrangular in cross section when in an unstressed condition as shown in the jackets of the middle pack 12. Each of these jackets is, by preference and as shown, made of a single sheet of elongated rectangular material 27, shown in the extended condition in Fig. 5. As seen in this view the sheet has paired parallel upper creasing lines 28, like middle fold lines 29, and like lower crease lines 30, these six fold lines being utilizable in folding each sheet into the open-ended jacket shown in end elevation, for example, in the upper portion of Fig. 2.

Between the crease lines 28 each jacket sheet has through it an inner pair of circular holes 31 and an outer pair of circular holes 32, the diameters of all these holes being the same as the space between the fold lines 28, thus providing a row of four symmetrically arranged holes which extends transversely of the sheet 27. A like row of holes 33, 34 is provided between the fold lines 30. When the jackets are completed by adhering their end flaps 35 and 36 in place as shown in Fig. 2, holes 31 register with holes 33 and holes 32 with holes 34.

Each of the completed jackets has fed through its holes 31 and 33 one of a series of binding members 40 consisting of springy material yet sufficiently rigid to releasably fasten the jackets in place by having their end portions disposed in an interlocked relation to the wire runs 8 and 9, as well shown in Figs. 3 and 4. Any jacket thus attached to said wire runs may readily be removed by moving it along the wires to a spaced relation to the other jackets and then, by a turning movement, disengaging the ends of its binding strip from the wire runs 8 and 9.

When it is desired to secure the jackets to the panel in a more permanent manner, as is necessary with wider panels, the binding strip 40 of the jacket to be attached is fed through all four of the aligned holes provided for it in the completed jacket and is at the same time brought into an underlying, interlocked relation to both the wire runs 8 and 9, as shown in Fig. 6. This is readily accomplished because the holes (see Fig. 6) 31—33 and 32—34 come at opposite sides of each wire run and are sufficiently far apart to allow the binding strip to underlie the intervening deflected portions 37 of the jacket wall, as shown in this view.

Owing to the overlapping of the end flaps 35, 36 in relation to adjacent wall portions of the completed jackets a double, reinforced jacket wall results where the material is placed under additional strain by being deflected by the binding strips, hence the durability of each jacket is thus prolonged.

In the face and edge portions of certain of the completed jackets, as seen in Fig. 1, are provided circular windows 41 and 42 wherethrough appear colored areas upon a contained indicator

sheet, further indicating the character of the indexed material.

As shown in Fig. 2 the lower jacket of the pack 12 contains a sheet 43 having a colored outer part 44 which is angularly deflected to cause it to underlie the color display window 42 (Fig. 1). Variously colored sheets may be inserted into other jackets, as indicated by conventional color-indicating shading in the color windows 41. A code of color combinations can be used as an aid to the observer to determine at a glance the contents of a given jacket.

Both the front and back of the completed jackets 25 may carry observable recorded data. The matter 25w on the upper face of the middle pack of Fig. 1 is in plain view, and the matter 25x on the reverse side of the upswung jacket 25 at the top of the view is also clearly readable.

Each attached jacket has a flat, rectangular surface along its free edge, the width of said surface being equal to the thickness of the filled jacket. Upon this surface is inscribed an indexing line 45 designative of the contents of the jacket. This index line is clearly readable whether the jackets are in a pendant, collapsed position as shown in the lower pack 13 in Figs. 1 and 2, or when positioned in a horizontal manner as in the central, filled pack 12, or when deflected upwardly as in the pack 14. It will readily be seen that this occurs as a result of the parallelogram formed by the four walls of the open-ended jackets, and that the jacket, when swingably attached to an upstanding panel, will always maintain in a vertical, readable position the index line 45 throughout all angular adjustments to which the jacket may be swung.

Cards, sheets of paper, etc. may readily be inserted into each jacket because it has open ends which are entirely unobstructed before the jacket is attached to the panel. Or, even while a jacket remains attached in the manner shown in Figs. 3 and 4, owing to the springiness of its binding strip 40 together with the resiliency of the retaining rods and panel it may, without detachment, be sufficiently withdrawn from between the flanges 6 and 7 to entirely unobstruct one or both of its ends preparatory to placing papers within it. After the jacket has been attached the panel flanges 6 and 7 partly cover its ends and aid in keeping in place its contents.

In Figs. 1 and 2 the upper jacket is shown vertically positioned with its back side abutting against the front face of the panel 5, the lower side of said jacket resting on the backwardly directed arms or short runs 46 of the wire. It will be seen that these runs are sufficiently long to allow the upper parts of the vertical wire runs 8 and 9 to swing far enough from the panel to allow room for the strap-like binding strip 40 when the latter is horizontally positioned in an underlying relation to said arms 46.

A tie rod 50 is shown having at each end a curl forming an eyelet, the wire runs 8 and 9 passing through said eyelets. One or more of these tie rods may be advantageously used to segregate certain packs in groups while they are undergoing revision or reclassification, as for example middle pack 12 shown in Figs. 1 and 2.

The operation of the device will for the most part be readily understood from the foregoing description, but some additional explanation thereof may be necessary to make it clear how, when a pack of filled jackets is moved upwardly along the attaching strips 8 and 9 to the limit of its travel on the slide the upper jacket of such a

pack will be caused to swing automatically from a more or less horizontal position to the vertical position which the upper jacket occupies as shown in Figs. 1 and 2.

It is to be understood that the backwardly directed arm 16 at the upper end of each wire run 8 and 9, when made by a bending machine, will have its inner angle slightly rounded where it joins the main run. Hence when the upper edge portion of the narrow binding strip 40 of the ascending jacket encounters this rounded part it will be backwardly deflected and further upward pressure against the attached part of the jacket whether by the next underlying jacket or directly by the hand of the operator, will advance its said binding strip toward a horizontal position in respect to its width, causing said binding strip to swing the jacket to which it is attached to the upstanding position as shown in the upper portions of Figs. 1 and 2. And it is obvious that when the jacket is swung forwardly and forced downwardly to return it to its original position its binding strip will retrace its course in relation to the wire.

What is claimed is:

1. In a jacket file of the kind described, an upstanding panel, a pair of parallel spaced apart retaining strips mounted upon said panel in an overlying spaced relation to the face thereof, each of said strips having at its upper end a backwardly deflected portion which loosely extends through a hole in said panel which is spaced considerably below the upper edge of said panel, said backwardly deflected portions being united behind the panel by a cross run, the free ends of said strips being anchored to a lower part of the panel, a plurality of separate jackets, each of which has a straight edge portion which is slidably attached to said strips to slide along them to and from an adjacent relation to the upper end of said panel, said attached edge portion having a width substantially equal to the offset from the face of the panel of the upper end portion of each of said strips, and means extending through the attached edge portion of each jacket and underlying said strips to automatically backwardly deflect said jacket when it arrives at the upper limit of its travel.

2. In a jacket file of the kind described, an upstanding panel, a pair of parallel spaced apart retaining strips mounted upon said panel in an overlying spaced relation to the face thereof, each of said strips having at its upper end a backwardly deflected portion which loosely extends through a hole in said panel which is spaced considerably below the upper edge of said panel, said backwardly deflected portions being united behind the panel by a cross run, the free ends of said strips being anchored to a lower part of the panel, a plurality of separate file jackets each having a back edge portion whereby it is swingably and slidably attached to said retaining strips, said jackets each being of a slab-like shape to enable them to be grouped together in their mounted position in a superimposed flatwise contacting relation, the aforementioned backwardly deflected runs of said strips forming abutments whereby at the end of the upward travel of an attached pack of said jackets the uppermost jacket is flipped from a horizontal to an upstanding position with its back face abutting against the upper portion of the front face of the supporting panel.

3. In a jacket file of the kind described, an

elongated panel having through it two apertures located in an end portion of said panel and on a line extending transversely thereof, said apertures being on opposite sides of the midlength of the panel and substantially equidistant from its side edges, a wire consisting of two main runs extending lengthwise of the panel, said runs being continued at their upper ends as backwardly directed arms which extend loosely through said apertures, the central portion of the wire uniting the back ends of said arms, said main wire runs being attached to the lower portion of the panel and being swingable outwardly from the panel as far as the lengths of said wire arms will allow, a data-containing jacket of a slab-like shape, and means carried by an edge portion of said jacket to attach it to said main wire runs in a slidably swingable manner, said jacket being slidably upwardly along said main wire runs to their upper ends and then backwardly swingable to an upstanding position wherein it rests upon said arms and its back side abuts against the upper part of the front face of said panel.

25. 4. In an indexed file, an upstanding vertical support, a jacket having walls of semi-rigid sheet material disposed in a quadrilateral relation to each other, and means for attaching said jacket to one side edge of said support to be swung through a vertical plane, the free side edge of said jacket having index matter upon its face, said face lying in a substantially vertical plane at whatever position the jacket is swung in relation to said upstanding support.

35. 5. In an index file, an upstanding supporting panel, a pair of parallel, spaced apart longitudinally extending retaining strips carried by said panel in a spaced, overlying relation to one of its faces, the lower extremity of each of said strips being constructed and arranged to grip the lower edge of said panel, the upper extremity of each of said strips being backwardly deflected in a short run and extending through an aperture spaced considerably down from the top of said panel, said short runs being in turn laterally deflected to maintain each short run in its aperture, a plurality of data-containing jackets each slidably fastened to both of said strips, and a tie rod bridging the space between said strips and having its end portions slidably attached to them dividing said jackets into groups.

55. 6. The subject matter of claim 5 and, said laterally deflected portions of said short runs being united to form the midlength portion of the retaining strips considered as a whole and said tie rod consisting of a wire having end curls whereby it is attached to said strips.

60. 7. In a self-labeling visibly indexed jacket file, an upstanding back panel, a pair of parallel spaced apart retaining strips mounted upon said panel in an overlying spaced relation to the face thereof, a plurality of separate file jackets each of quadrangular cross section and each of which is attached to said retaining strips to slide along them to and from an adjacent relation to the upper end of said panel, each of said file jackets having an index line along the edge thereof farthest from its attached side, and means carried by each said jacket and co-operating with said retaining strips to deflect bodily the uppermost of said file jackets when it arrives at its uppermost position on the panel.

70. 8. A jacket file according to claim 7, wherein locking means is provided for detachably con-

necting each file jacket to said retaining strips.

9. A jacket file according to claim 7, wherein guide flanges are provided along the sides of the panel for preventing extrusion of the contents of the jacket.

10. A self-labeling visibly indexed jacket file comprising a file jacket support, a plurality of separate jackets for containing removable sheets and cards, and means to slidably attach said jackets to said support, said means including a plurality of retaining strips upon which said jackets are individually slidable, said jackets each comprising an elongated sheet of paper furnished with pairs of apertures, the apertures of each pair being located adjacent to and on opposite sides of one or the other of said retaining strips, and a locking strip extending through a plurality of said paired apertures when opposite end portions of said sheet of paper are folded inwardly so as to be superimposed one upon the other and adhered to retain each file jacket cooperatively with said retaining strips, said sheet being creased whereby in its folded condition it forms an enclosure quadrangular in cross section with open ends.

11. In a device of the kind described, an up-standing vertical panel, a plurality of record carriers quadrangular in cross section, means to mount said carriers upon said panel in a vertically slideable manner, the free side edge of each of said carriers having index matter upon its face, said means including arms projecting through apertures in said panel and being laterally deflected in a spaced relation to the back side thereof to automatically swing the uppermost carrier from an angular relation to said panel to a parallel relation thereto when said carrier is moved to the upper limit of its travel in relation to said panel.

12. A jacket file according to claim 3, wherein said data-containing jacket is composed of walls of semi-rigid material disposed in a quadrilateral relation to each other thereby forming an enclosure quadrangular in cross section and each angle forming the quadrangular cross section being a right angle.

13. A jacket file according to claim 3, wherein said data-containing jacket is composed of walls of semi-rigid material disposed in a quadrilateral relation to each other thereby forming an enclosure quadrangular in cross section with open ends, each angle forming the quadrangular cross section being a right angle and the free side edge of said jacket having index matter on its face.

14. A self-labeling visibly indexed jacket file comprising a file jacket support, a plurality of open-ended jackets of quadrangular cross section for containing removable sheets and cards, means to slidably attach each of said jackets to said file jacket support, each of said jackets having an index line along the free side edge thereof farthest from the attached side, and means carried by said file jacket support and cooperating with said slidably attaching means whereby the uppermost jacket is bodily deflected when it reaches its topmost position.

15. A self-labeling visibly indexed jacket file comprising a jacket file support or slide, an open ended jacket of quadrangular cross section, means to slidably attach said jacket to said support or slide, and means extending through the attached edge portion of said jacket and cooperating with said attaching means to automatically backwardly deflect said jacket when it arrives at the upper limit of its travel.

16. A self-labeling visibly indexed jacket file comprising a jacket file support or slide, an open ended jacket of quadrangular cross section slidably mounted upon said support or slide, each angle forming the quadrangular shape being a right angle, there being a crease line along each right angular bend thereof, means to slidably attach said jacket to said support or slide, and means detachably extending through the attached edge portion of said jacket and cooperating with said attaching means to automatically backwardly deflect said jacket when it arrives at the upper limit of its travel.

17. A self-labeling visibly indexed jacket file comprising a jacket file support or slide, an open ended jacket of quadrangular cross section slidably mounted upon said support or slide, each angle forming the quadrangular shape being a right angle, there being a crease line along each right angular bend thereof, means to slidably attach said jacket to said support or slide, and means detachably extending through the attached edge portion of said jacket and cooperating with said attaching means to automatically backwardly deflect said jacket when it arrives at the upper limit of its travel.

18. As an article of manufacture, a file jacket for containing a plurality of removable sheets and cards comprising a single sheet of elongated rectangular material having paired parallel creasing lines adjacent each of its opposite ends and like middle fold lines spaced equidistantly therefrom, all of said lines being utilizable in folding said sheet into an open ended jacket quadrangular in cross section, there being an inner and an outer pair of circular holes between the first and second of said lines at each end and of the same diameter as the distance between the lines of each pair, thereby providing a row of four symmetrically arranged holes extending transversely at each end of the sheet, the inward spacing of the first said paired parallel creasing lines providing end flaps to overlap adjacent wall portions when the jacket is folded in the shape aforesaid thus bringing each pair of inner and outer holes at each end into registry respectively with corresponding holes at the other end, and binding members extending through said registered holes to releasably fasten the ends of said sheet together to maintain said quadrangular shape.

JOHN T. QUIGLEY.
